UNITED STATES PATENT OFFICE.

HENRY PERCIVAL SALSBURY, OF LONDON, ENGLAND.

LIFTING JACK.

Application filed December 5, 1927, Serial No. 237,916, and in Great Britain November 23, 1926.

This invention relates to certain improvements to be used in connection with lifting jacks such as employed for lifting the axles of motor and other vehicles, the main object of the invention being to provide means which will allow the jack to be conveniently moved into its operative position.

The means constructed according to the present invention for guiding a lifting jack in position comprises in combination an elongated guiding plate secured or adapted to be secured to either the main spring or the axle of the vehicle and a member secured to or capable of being secured to the jack and adapted to engage with the said elongated guiding member, the latter extending sufficiently far to allow the jack to be readily brought into engagement therewith.

The invention also consists in the various constructions and arrangements hereinafter more particularly described by way of example, with reference to the accompanying drawings, in which:—

Figures 1, 2 and 3 are respectively an elevation, a plan view and an end view of one arrangement according to the invention, in which the guiding means on the vehicle are secured to the main spring;

Figure 4 is an elevation of the same form of construction of guiding means as shown in Figures 1-3, the said means being, however, adapted for being secured to one of the axles of the vehicle;

Figure 5 shows in cross section a modification of guiding head provided on the jack;

Figures 6 and 6^a are cross sections of modified guiding means provided on the vehicle and jack respectively, whilst

Figures 7 and 7^a are similar views of a further modification;

Figure 8 illustrates in sectional elevation a modification of the means by which the guiding means are attached to the vehicle, and

Figure 9 is a perspective view of a detachable head or guide to be used in an arrangement according to the present invention.

Referring to the form of construction illustrated in Figures 1-3, *a* is an elongated plate secured to the main spring *b* of the vehicle, and *c* are side flanges with inturned ends secured to the plate *a* to form a channel-like guiding member, *d* being an end piece secured to the free ends of the said flanges in order to keep them in position. *e* is a wedge-shaped member which is preferably interposed between the guiding members

a, *c* and the spring *b*, being capable of being slid into its proper position under the spring along a slot *e*₁ provided in the plate *a*, through the intermediary of a pin, bolt or 60 the like *f* and be firmly secured between the said plate and the spring *b*. *g* is a hole provided in the plate *a* in which a head can be inserted for securing the plate to the spring. The guiding means provided on the jack consist of rollers *h* secured to the top of the jack *i* and capable of rolling along the inwardly projecting ends *c*₁ of the side flanges *c* of the guiding member.

Referring to the form of construction illustrated in Figure 4, *j* is a bracket secured to the plate *a*' of the guiding member and formed in such a manner as to conform to the contour of the axle and be capable of being secured thereto, being for this purpose used in conjunction with a top clamp and clamping bolts (not shown).

Instead of providing the jack with guiding rollers, the top of the jack may be provided with a head *k* as shown in Figure 5, capable 80 of being easily slid along the guiding flanges *c*.

According to a further modification, as shown in Figures 6 and 6^a, the guiding member *k*² provided on the jack may be formed 85 with side flanges *k*₁ in such a manner that the jack can be guided externally along the edges of a guiding plate *a*² secured to the vehicle. A slightly different construction of this modification is illustrated in Figures 7 and 7^a, in 90 which the guiding plate *a*³ secured to the vehicle is formed with a convex lower surface, and the upper surface of the guiding member *k*³ provided on the jack is correspondingly shaped at *k*⁴ to engage with the said convex 95 surface on plate *a*.

It is to be understood that the guiding means may be modified in various respects. Thus for instance the wedge-shaped member *e* hereinbefore described with reference to Figure 1, may be formed with an extension 100 adapted to be inserted underneath the central part of the main spring and be secured thereto by bolts, clamping or otherwise, instead of the plate *a* being directly secured thereto. This form of construction is illustrated in Figure 8, in which *e*² is the extension formed on the wedge-shaped member *e*² secured to the plate *a*².

The guiding means provided on the vehicle 110 and the jack may also be modified in various respects. Thus, for instance, if use is made of

a sufficiently thick plate, the same may be provided with recesses adapted to engage with projections formed in the guiding member secured to the lifting jack.

- 5 According to one particular form of construction as illustrated in Figure 9, the guiding means attached to the jack may comprise a suitably shaped block l and lateral members m having a middle portion m_1 by which they can be attached to the said block and upper and lower curved flanges m_2, m_3 , the said lower flanges m_3 being capable of being attached to the head of the jack and the upper flanges m_2 serving as guiding means.
- 10 The guiding means on both the vehicle and the head of the jack may be made of any suitable material and lifting jacks may be permanently provided with a guiding member intended to engage with guiding means pro-

vided on the vehicle. Further, the forms of construction hereinbefore referred to may be modified in various other respects without in any way departing from the spirit of the invention as set out in the claim.

What I claim is:

25 In combination a vehicle spring, an elongated channelled guiding member firmly secured at one end to the spring, a member on the jack movably engaged with said guiding member whereby the jack may be guided into operative position beneath the spring, and a wedge-shaped member inserted between the vehicle spring and the guide member inwardly of the opposite end of the latter.

30 In testimony whereof I have signed my name to this specification.

35 HENRY PERCIVAL SALSBURY.
